UNITED STATES PATENT OFFICE.

PATRICK McMAHON, OF WHITESTONE, NEW YORK, ASSIGNOR TO THE YALE & TOWNE MANUFACTURING COMPANY, OF STAMFORD, CONNECTICUT.

LOCK.

SPECIFICATION forming part of Letters Patent No. 451,878, dated May 5, 1891.

Application filed February 14, 1891. Serial No. 381,446. (No model.)

To all whom it may concern:

Be it known that I, PATRICK McMAHON, of Whitestone, in the county of Queens, State of New York, have invented certain new and useful Improvements in Locks, of which the following is a specification, reference being had to the accompanying drawings.

The object of my invention is to produce improvements in master-key locks of the class in which the tumblers are set by the rotation of a key and not by its insertion after the manner shown, for instance, in my patent, No. 429,361, of June 3, 1890. To accomplish this object I use two sets of tumblers, one set being actuated by the key, and these in turn actuating the other set of tumblers, which I will call the "dogging-tumblers." The thickness of the key-actuated tumblers with respect to the dogging-tumblers is such that two of the former act upon one of the latter and upon no other, so that with proper bittings either a master-key or a change-key can be made to operate the lock by operating different key-tumblers. Those tumblers which I call the "dogging-tumblers" serve to hold the bolt in fixed relations to the case in the locked position, or alternately in the locked and unlocked positions, if preferred, and in order to move the bolt the dogging-tumblers must be moved by the key out of engagement with it and held at a straight line of division between the two sets of tumblers until by the further rotation of the key the bolt may be cast or retracted. In order to accomplish this result, I may secure the dogging-tumblers in a chamber fixed to the case and locate the key-actuated tumblers upon a movable part—such as a plate—which actuates the latch or the bolt or the tail of the bolt itself, or the key-actuated tumblers may be made stationary, and the dogging-tumblers may be carried upon the movable part. It is plainly immaterial which set of tumblers is made movable and which stationary so long as one set is adapted to lock the bolt in the case.

In the accompanying drawings, Figure 1 is a plan view of my invention as applied to a latch, showing the case with the cap-plate removed and the latch in the locked position. Fig. 2 is a similar view showing the latch in the unlocked position. Fig. 3 shows my in-

vention as applied to a dead-bolt, the bolt being retracted. Fig. 4 is a similar view showing the bolt in the locked position. Fig. 5 is a view of a modified form of my invention, 55 showing dogging-tumblers carried on the bolt and the bolt in the retracted position. Fig. 6 is a view of a similar modification as showing the bolt in the cast position. Fig. 7 is a vertical section through the key-hole of Fig. 60 5. Fig. 8 is a view of the detached parts of my invention as shown in Figs. 1 and 2. Fig. 9 is a detached view of the bolt and tumblers as shown in Figs. 3 and 4. Fig. 10 is a detached view of the bolt and tumblers as shown 65 in Figs. 5, 6, and 7.

Referring now to Fig. 1 of the drawings, in which I have illustrated a latch fitted with my master-key device, A indicates the case, and B the latch moving upon suitable bearings therein.

C indicates a spring-actuated lever, that is pivoted to the case at C' and may be pivotally connected with the tail of the latch, and which is adapted to be operated from the inside only 75 in the usual manner by a knob and spindle. These parts are of well-known construction. My invention when applied to a latch relates to the means for operating it from the outside by means of keys.

D indicates a carriage or movable plate adapted to be moved upon suitable bearings in the direction of movement of the latch. It is provided at its upper end with a projection E, which is adapted to engage with the 85 lower end of the lever C, and thereby in its backward movement to draw the latch. In its lower part it is provided, as usual, with a recess F, within which and against the sides of which the bit of the key operates to move 90 the carriage.

G indicates a transverse guide-slot in the carriage, within which is fitted a guide-pin H, that projects from one side of the case and preferably extends to the other side thereof. 95

I indicates another such pin, against which the top of the carriage moves, and which assists to keep it in position.

K indicates a transverse slot in the body of the carriage, within which is fitted the chamber-case L, that is fastened to one side of the case integrally or otherwise and extends to 100

the other side. This chamber-case is narrow at one end and fits into the mouth M of the slot K, by which means the carriage is allowed to freely reciprocate within the case, but within fixed limits. By reason of the guide-pin H and the chamber-case being fitted into the transverse slots the carriage is caused to move truly and evenly under the impulse of a key, and motion may thereby be communicated through the key to the bolt with which the carriage engages at its upper part. Upon the top of the lower part of the carriage is provided a cage N, that consists of four walls secured by any suitable means to the carriage. The lower wall is cut away at N', so as to allow the free sweep of the key-bit within the cage, and is provided in the middle of its upper side with a vertical slot O, which is prolonged by projections P, extending downwardly from said wall. Through the larger part of the chamber-case L is cut a chamber or vertical slot Q of the same width as the slot O, and so located that when the latch is in the locked position the slots O and P form one continuous slot. Within the chamber Q are loosely placed a number of tumblers, which I will call "dogging-tumblers" R. One of these tumblers is sufficient for the practical operation of my lock; but I generally prefer to use more. The dogging-tumblers, by gravity or by the action of springs S, that may be wrapped around the pin H and bear at one end against the pin I and at the other end in slots T against the ends of the dogging-tumblers, tend to pass from the chamber O into the slot P when the latch is in the locked position and so hold the carriage to the chamber-case. To separate these parts by the use of either a master-key or a change-key, I provide within the cage N a number of key-tumblers U, two tumblers being provided for each dogging-tumbler. These tumblers consist, preferably, of flat pieces of metal notched at U' to receive the projections P of the upper wall of the cage, and each is provided with a projection V of the same width as the dogging-tumblers. The tumblers are of such thickness that two of them are adapted to operate one of the dogging-tumblers and no more, so that by raising any one of said key-tumblers one of the dogging-tumblers will be raised. When the tumblers have been raised until their points of division coincide with the line where the upper wall of the cage and the tumbler-case meet, the carriage will be free to move under the operation of the key until it has retracted the latch. Then the key, having been turned backward, may be withdrawn. Thereupon under the impulse of the

spring-actuated lever C the carriage will be thrown back until it reaches the position from which it started, when the chamber O and the slot P again coinciding the dogging-tumblers will slip from the former into the latter and lock the parts, as before.

From the foregoing description it will be perceived that by changing the length of the projections V and the bits of the key a great number of changes in the combinations may be produced. It will also appear that two keys may be made to unlock the door without changing the combination, because one key may be made to operate the dogging-tumblers through one set of key-tumblers and the other key may be made to operate them through another set, and both sets of key-tumblers act independently.

In Figs. 3 and 4 of the drawings is shown my improved construction as applied to a dead-lock. The principle is the same; but inasmuch as it is necessary to withdraw the key both in the locked and unlocked positions of the bolt the upper wall of the cage N is provided with two slots, into which the dogging-tumblers move, and thus connect the carriage and the tumbler chamber-case and dog the bolt.

In Figs. 5, 6, and 7 of the drawings is illustrated a modification of my invention, in which the cage N and tumblers are secured to the case of the lock, and the dogging-tumblers are carried in a chamber-case that forms a part of the bolt. In this instance, while the operation by the key is precisely the same, the key-tumblers are kept transversely stationary and the dogging-tumblers are movable.

What I claim is—

1. In a lock, the combination of two key-actuated tumblers, each adapted to be set by the rotation of a key, and a dogging-tumbler actuated by either of said key-tumblers, substantially as set forth.

2. In a lock, the combination of the two key-actuated tumblers, each adapted to be set by the rotation of a key, a dogging-tumbler actuated by either of said key-tumblers, and a tumbler-carriage, said carriage by the continued rotation of the key being moved relatively to the fixed tumbler-chamber, substantially as set forth.

In testimony of all which I have hereunto subscribed my name.

PATRICK McMAHON.
